US0D1098744S

(12) United States Design Patent (10) Patent No.: US D1,098,744 S
(45) Date of Patent: * Oct. 21, 2025

(54) STORAGE CONTAINER

(71) Applicant: GIFU PLASTIC INDUSTRY CO., LTD., Gifu-ken (JP)

(72) Inventors: Kentaro Okamura, Gifu (JP); Hirokuni Yamamoto, Tama (JP)

(73) Assignee: Gifu Plastic Industry Co., Ltd., Gifu-ken (JP)

() Term: 15 Years

(21) Appl. No.: 35/521,296

(22) Filed: Aug. 30, 2023

(80) Hague Agreement Data

Int. Filing Date: Aug. 30, 2023

Int. Reg. No.: DM/232509

Int. Reg. Date: Aug. 30, 2023

Int. Reg. Pub. Date: Jun. 14, 2024

(30) Foreign Application Priority Data

Jul. 10, 2023 (JP) ..... 2023-014210 D

(51) LOC (15) Cl. 03-01

(52) U.S. Cl.

USPC D3/276; D3/905; D3/294

(58) Field of Classification Search

USPC D3/273, 276, 279, 282, 284, 294, 295,
D3/302, 905, 262, 281

CPC B25H 3/02; B25H 3/021; B25H 3/006;
B25H 3/003

See application file for complete search history.
